UNITED STATES PATENT OFFICE.

CHARLES H. CROWELL, OF BROOKLYN, NEW YORK.

TAPE MOISTENING AND SEVERING MACHINE.

Application filed May 27, 1919. Serial No. 300,102.

To all whom it may concern:

Be it known that I, CHARLES H. CROWELL, a citizen of the United States, and resident of the borough of Brooklyn, county of 5 Kings, city and State of New York, have made a certain new and useful invention relating to Tape Moistening and Severing Machines, of which the following is a specification, taken in connection with the accompanying drawing.

This invention relates especially to machines for severing and moistening gummed tape or printed labels which may be made up in perforated strips in roll form for application to packages or articles. One or more rolls of such perforated paper or cloth tape which may be previously gummed may be arranged on the machine and a strip from each roll may be led into engagement 20 with a feed roll, the operation of which is manually controlled so that it is only intermittently operated when the perforated labels or strip material is to be fed forward over the feed table. Beyond this feed roll a 25 continuously operating pulling or severing roll may be arranged to feed forward the strip and to sever the same at the adjacent line of perforations when the feed roll stops. The severing roll or other device may be arranged in connection with a moistening or 30 gumming roll to render the strip material or printed label adhesive before it is delivered upon a corrugated or other delivery table, for example.

In the accompanying drawing showing in a somewhat diagrammatic way illustrative embodiments of this invention,

Fig. 1 is a vertical section.

Fig. 2 is a partial side elevation of the 40 further side of the machine showing the control devices.

Fig. 3 is a partial side sectional view showing the change gearing.

Fig. 4 is an enlarged transverse section 45 taken along the line 4-4 of Fig. 3.

Fig. 5 is a top view.

Fig. 6 is an end view on an enlarged scale; and

Fig. 7 is a detailed sectional view showing another form of construction.

The machine may be provided with a standard or base 1 to which the side plates or frame members 2 may be secured in any desired way. An outer removable frame member 3 may, if desired, be suitably connected to the base or adjacent frame member

and assist in supporting the elements and moving parts, such as the shaft or support 26 on which the one or more supply rolls 25 of tape or labels may be arranged and supported. A number of such supply rolls of perforated gummed tape or labels may be supported side by side and preferably separated by intermediate spacing disks or members 24, suitable end plates 27, 28, being preferably mounted on the support so as to yieldingly press the rolls together by the action of the spring 29 when the set screw 30 in the hub of the plate 27 has been adjusted. In this way as many as four or 70 more strips of such gummed or ungummed tape or perforated labels may be led through the machine and severed along such perforated lines of severance as 83 so as to form separate printed labels or tape strips 75 for application to packages. The moving parts of the machine may be operated in any desired way and for some purposes it is advantageous to have an electric or other motor 4 mounted in any convenient position on 80 the base of the machine and as indicated this motor may have its pulley 5 connected by the belt 6 with the drive pulley 7 on the drive shaft 85.

The tape strips may be led along the feed 85 table 82 and beneath the guide roll or device 23 so as to be engaged by a feed roll such as 18, which may be mounted to cooperate with this feed table and feed the strips along the same in connection, if desired, with a feed presser 31 which may be yieldingly forced against the feed roll and be provided with a rubber or other yielding face 32. This presser may have its shaft mounted in the arms 19 secured to the rock 95 shaft 20 and the releasing lever 22 may be connected to one of these arms and normally actuated by the spring 21 to force this feed presser against the feed roll and ensure the proper grip upon the paper strips. 100 This feed roll which may be mounted on the feed shaft 15 is preferably intermittently power operated or controlled in its operation so as to feed forward one or more strips. This may be effectively accomplished 105 by having a slip friction clutch between this roll and its driving devices and by positively stopping the roll at the desired intervals to feed forward the increments of tape desired, to correspond to the length of 110 the individual printed or other perforated labels or strips being handled. In order

to make the operation of this feed roll adjustable to suit different lengths of labels or strips change gears may be introduced between the stop devices for the feed roll and the roll shaft and one convenient form of mechanism for this purpose may comprise the drive pinion 8 on the drive shaft 85 as shown in Fig. 3 which may mesh with the gear 9 on the main shaft 54 of the machine. A yieldable friction or slip clutch such as the disk or clutch members 10 shown in Fig. 6 may be arranged on this shaft 54 and forced together as by the adjusting nuts 95 so that normally the feed gear 11 is rotated in unison with the gear 9, but slipping of this gear 11 can take place about the drive shaft when its rotation is interrupted. Any suitable change gear may be used between this feed gear 11 and the feed shaft 15, and, for example, the change gears 12, 13 may rotate together about the stub shaft 49 adjustably supported in the sector slot 94 so as to be rotated by the feed gear, the gear 13 meshing with the feed pinion 14 on the feed shaft 15. By replacing one or more of these change gears the ratio between the feed gear 11 and the feed pinion and feed shaft may be adjusted within considerable limits so that different lengths of labels or tape strips may be supplied by the machine. Of course, if desired, the feed presser roll 31 may be rotated in unison with the feed roll 18 by suitable meshing gears 16, 17 on their shafts as shown in Fig. 5.

A convenient stop device for controlling the mechanical rotation of the feed roll may comprise a control wheel or stop disk 33 which may be removably mounted on the drive shaft 54 and rotated in unison with the feed gear 11 by any suitable connection such as the pins 91 on the feed gear which may have ends fitting within the holes 90 in this stop disk, as shown in Fig. 2. One or more stop members or projections, such as 34, 35, may be arranged on these interchangeable stop disks and one, two or more such stop members may be formed on each disk so that by interchanging them a still further range of tape or label length may be readily secured. A detent device of any suitable character may cooperate with this stop disk to restrain its normal tendency to rotate as long as the motor is in operation, and the pivoted control device or detent 36 may be arranged as indicated in Fig. 2 so that this spring actuated member may have its projecting detent 86 normally in the path of the stop member 34 on the control wheel 33, while the actuating handle or lever 39 pivoted about the pin 40 may be manually depressed so as to move the connected actuating link 38 and swing this control device about its pivot 37 so as to remove this detent from the path of the

stop member and allow the stop disk to rotate through a half or any other desired part of a revolution until the next stop member comes into engagement with the detent device. In order to ensure the definite operation of this control device it may be provided with a plurality of alternatively engaging detents or projections so that the movement of the actuating lever when it throws the detent 86 out of engagement with the stop member throws another detent 87 into the path of these stop members so that the succeeding stop member engages this detent and its movement is interrupted if the actuating handle is kept in its depressed position. When this actuating handle is released the detent instantly returns to its normal position shown in Fig. 2 through the action of these parts and the restoring spring on the detent. In this way by the use of the desired disk and the change gears between the feed gear and the feed shaft a single movement of the actuating lever or handle allows the feed roll to revolve to such extent as to feed forward a single length of the perforated tape or strip between the lines of perforation or other weakening 83, 83', as shown in Fig. 5, which may be previously formed in the paper strips. Such an intermittent feeding device may of course be advantageously used to feed forward adjustable length pieces of unsevered tape in connection with various forms of severing and moistening mechanism.

The severance, delivery and moistening of each successive label or perforated strip length may be conveniently effected by continuously operating, pulling, severing or moistening rolls or devices adapted to engage each successive length of strip supplied by the feed roll and pull it forward and sever it and moisten or gum the strip and deliver the same for application to a package. For this purpose suitable pulling or severing rolls or devices may be continuously operated in any desired way as by connecting or gearing them to the motor or driving connection of the machine and as shown in Fig. 1 the rubber or other pulling roll 57 may be mounted adjacent and ahead of the feed roll 18 and may, if desired, have a cooperating pulling presser roll 58 mounted in arms 59 normally actuated by springs such as 60 to swing them about the pins 61 and maintain the desired engagement between these cooperating presser rolls, which may be geared together as by the gears 55, 56 on their shafts as shown in Fig. 4.

The moistening device which may be of any suitable construction may comprise the moistener roll 67 which may as indicated in Fig. 6 be formed with longitudinal corrugations and also, if desired, with annular

recesses 66 with which may cooperate stripper blades or knives 74 yieldingly mounted on the bar 73 to disengage the paper strips from the moistener. A moistening presser roll, such as 68, may be formed with separated annular ribs 69 and be mounted in rock arms 70 supported by the pins 71 while the springs 72 normally force this presser roll down upon the paper strip or on the moistener roll beneath when the strip is not interposed. The moistening or gumming material may be supplied to this moistening roll in any suitable way as through the water roll 65 of metal or other suitable material which may be mounted on the shaft 48 so as to rotate within the tank 75 and carry up to the moistener water or other liquid 76 from this tank. These rolls may all be positively driven from the drive gear of the machine, if desired, and for this purpose as indicated in Fig. 3, the shaft 48 of the water roll may be provided with a gear 45 with which the gear 43 may mesh and be engaged by a change gear 42 on the adjustable stub shaft 50 mounted within the slot 51 and also supporting the gear 41 rotating in unison with the gear 42 and meshing with the gear 9 on the main shaft 54. The shaft 46 on which the pulling roll 57 is mounted may be provided with a pinion 44 meshing with the gear 43 and as shown in Fig. 6 the gears 62, 63 and 64 may drive the moistening and cooperating presser rolls from the water roll, if desired. In this way the motor of the machine may continuously operate the pulling and moistening rolls while the slip clutch connection between the feed roll and its gearing makes it possible to restrain the normal tendency of this gearing to operate the feed roll except when the actuating handle or lever is moved by the operator. Under these circumstances the feed roll rotates through a sufficient distance to feed forward a length of tape so that as indicated in Fig. 5 the end 83' of each label or tape strip may be fed forward until the line of severance 83 arrives at substantially this same position. In the meantime the pulling and moistening rolls which may sometimes be slightly underspeeded so that as soon as they engage the tape strips they pull the same forward at a slightly reduced rate, continue to operate after the feed roll stops, and this further rotation of the pulling rolls exerts sufficient tension on the tape strips so that they are pulled apart or severed along their weakened portions or lines of severance, as for example, between the printed labels on the strips. In this way accurate severance of the labels is always secured even when because of slight irregularity of feeding and so forth, the ends of these tape strips move forward or backward slightly from the predetermined or

mid position between the feed roll and pulling roll. There is thus no substantial danger that improper severance will occur and of course if for any reason such as wearing of the feed roll or slipping thereof, the tape ends get too far out of the desired alignment, they can be manually adjusted as indicated in Fig. 7 by releasing the feed presser roll 31 and manually pushing forward or backward one or more of the tape ends. Fig. 7 also indicates a desirable variation in this device which may be effected by spacing the pulling and moistening rolls somewhat more closely together so that still shorter lengths of gummed labels or tape strips may be handled effectively by the machine. After severance and moistening of the strips they may, if desired, be separated from the moistening roll by the spring pressed or yieldable stripper blades 74 resiliently held down on the moistening roll 67 as by the spring 77 and guided out on a delivery table 78 which may be adjustably or removably secured to the frame members as by the bolts 80 shown in Figs. 1 and 5 which may clamp the depending flange 79 of this table to the machine frame. This delivery table may advantageously be formed with narrow upstanding longitudinal ribs 81 to minimize contact between the gummed or adhesive side of the tape or labels which may be manually secured by the operator and applied to packages or articles. As shown in Fig. 5 four such label strips may be simultaneously fed forward every time the actuating handle 39 is operated so that four gummed strips or labels are thus delivered on the delivery table to be applied to packages of such character as to need four securing labels or sealing members. If desired, of course, a less number of supply rolls of wider tape or labels may be used in the machine and if it is desired to handle different packages one or more of these label strips may be manually withdrawn from the feed roll so as not to be fed forward thereby so that the machine may be very readily and quickly converted to deliver a greater or less number of strips within the limits of its capacity.

This invention has been described in connection with a number of illustrative embodiments, forms, devices, parts, sizes, proportions, mechanisms and materials, to the details of which disclosure the invention is not of course to be limited, since what is claimed as new and what is desired to be secured by Letters Patent is set forth in the appended claims.

I claim:

1. In severing and moistening machines for severing moistening and delivering individual perforated labels, a support to carry a number of supply rolls of such perforated, gummed, printed label strips, a

feed roll to engage said labels, continuously operating, pulling and moistening devices to engage said labels beyond said feed roll and moisten and deliver the same, and 5 means to mechanically operate said feed roll comprising a slip clutch and a detent to intermittently allow said feed roll to feed said label strips forward through substantially the distance between adjacent perforations and then hold said label strips to effect the severance thereof through the continued operation of said moistening devices.

2. In severing and moistening machines for severing, moistening and delivering individual perforated labels, a support to carry such perforated, gummed, label strip, a feed roll to engage said labels, continuously operating, pulling and moistening devices to engage said labels beyond said 10 feed roll and moisten the same, and means to mechanically operate said feed roll to intermittently allow said feed roll to feed said label strip forward through substantially the distance between adjacent perforations and then hold said label strip to effect the severance thereof through the continued operation of said moistening devices.

3. In severing and moistening machines for severing and moistening perforated strips, a feed table and a cooperating feed device to engage said strip, continuously operating severing devices to engage said strip beyond said feed device and moisten the same, and manually controlled means to 30 mechanically operate said feed device comprising change gearing to regulate the amount of movement of said feed device and intermittently feed said strip forward through substantially the distance between 35 perforations and then hold said strip to effect the severance thereof through the continued operation of said severing devices.

4. In severing and moistening machines for severing and moistening perforated strips, a feed device to engage said strip, severing devices to engage said strip beyond said feed device, and manually controlled means to mechanically operate said feed device comprising change gearing to intermittently feed said strip forward through substantially the distance between perforations and then hold said strip to effect the severance thereof through the operation of 50 said severing devices.

5. In severing and moistening machines adapted for use with perforated gummed paper tape, a manually controlled feed roll and means to mechanically operate said feed roll to a predetermined adjustable extent 55 comprising a stop disk having a stop member, and a cooperating control device, and continuously operating gripping moistening devices to engage the tape end received from said feed roll and tear the strip apart at 60 another perforated portion.

6. In severing and moistening machines adapted for use with perforated gummed paper tape, a manually controlled feed roll and means to mechanically operate said feed roll to a predetermined extent, and continuously operating gripping moistening devices to engage the tape end received from said feed roll and tear the strip apart at 70 another perforated portion.

7. In severing and moistening machines adapted for use with perforated gummed paper tape, manually controlled feed devices and means to mechanically operate said feed devices to a predetermined extent, and gripping moistening devices to engage the tape end received from said feed roll and tear the strip apart at 75 another perforated portion and means to readjust said strip with respect to said feed devices.

8. In severing and moistening machines adapted for perforated gummed paper tape, a gripping, pulling severing device, a feed roll to feed material to said severing device and means to mechanically operate said feed roll comprising a stop disk having a stop member, a manually actuated handle and a connected control device having a detent 80 adapted to be moved into the path of said stop member.

9. In severing machines adapted for perforated gummed paper tape, a gripping pulling severing device, a feed device to feed material to said severing device and means to mechanically operate said feed device comprising a manually actuated control device to limit the operation of said feed device to effect a substantially predetermined feeding action.

10. In severing or moistening machines for gummed paper tape, a feed roll and yieldable means to mechanically operate said feed roll comprising an interchangeable stop disk having spaced stop members, adjustable gearing between said stop disk and said feed roll to regulate the relative movement of said feed roll and stop disk, a manual actuating handle and a cooperating pivoted control device having a plurality of detents adapted to be moved alternatively into the path of said stop members and a spring to normally bring one of said detents into holding engagement with said stop members.

11. In severing or moistening machines for tape, a feed roll and yieldable means to mechanically operate said feed roll comprising a stop disk having spaced stop members, adjustable gearing between said stop disk and said feed roll to regulate the relative movement of said feed roll and stop disk, a manual actuating handle and a cooperating control device having a plurality of detents adapted to be moved alternatively into the path of said stop members.

CHARLES H. CROWELL.
